UNITED STATES PATENT OFFICE.

JAMES MILLS, OF CINCINNATI, OHIO, ASSIGNOR OF ONE-HALF TO ALBERT S. SMITH, OF CINCINNATI, OHIO.

SPEED-CHANGING MECHANISM FOR MACHINE-TOOLS.

SPECIFICATION forming part of Letters Patent No. 727,404, dated May 5, 1903.

Application filed January 7, 1903. Serial No. 138,095. (No model.)

To all whom it may concern:

Be it known that I, JAMES MILLS, a citizen of the United States of America, and a resident of Cincinnati, county of Hamilton, State 5 of Ohio, have invented certain new and useful Improvements in Speed-Changing Mechanism for Machine-Tools, of which the following is a specification.

The object of my invention is to provide 10 simple speed-changing mechanisms for varying the speed in machine-tools—such as lathes, shapers, milling-machines, planers, &c.—which mechanism is always in convenient reach of the operator and may readily be 15 changed to any speed desired without removing any of the parts or stopping the machine.

In illustrating my invention I have selected, in the first instance a metal-shaper in which it is desirable to make the speed-changing 20 mechanism as compact as possible to economize space. In the second example, wherein speed is not so much of an object, I have shown a very simple form of my invention. In this instance the friction, and consequently 25 the wear of the parts, is greatly reduced. In the third example I have shown my device changed to move in a straight path to adapt it to planers and similar uses.

The following description of the various 30 views of the drawings in the order set forth will enable those skilled in the art to which my invention relates to make and use the invention, and the claims following the description will point out wherein said invention, 35 which I claim as mine, differs from the preceding art.

Referring to the drawings, in which like parts are indicated by similar reference-letters wherever they occur throughout the various views, Figure 1 is a side elevation of a metal-shaper provided with my improvements. Fig. 2 is a detail view, upon a greatly-enlarged scale and in horizontal sectional view, taken through line $z-z$ of Fig. 4. Fig. 3 is a rear elevation, upon the same scale as Fig. 2, of the revolving case which houses a driving-pinion and which carries arms, the ends of which are perforated to receive stud-bearings, upon the end of which bearings are idle 45 pinions which couple alternately the pinion on the power-receiving shaft to either of the

cone-gears secured upon the power-transmitting shaft. Fig. 4 is a detail view, partly in front elevation and partly in vertical section, showing the speed-changing mechanism 55 mounted to be revolved axially around the power-receiving shaft, the cone-gears secured upon the power-transmitting shaft, and the gear-wheel to which the power is transmitted in shaping-machines. Fig. 5 is a plan view 60 of the same. Fig. 6 is a detail view, in transverse vertical section, taken on line $v-v$ of Fig. 5, but on a reduced scale. Fig. 7 is a detail view, in transverse vertical section, of a simple form of my invention, showing the armed 65 housing mounted eccentric to the power-receiving shaft in order to bring the idlers carried by the arms projecting inward from the revolving case or housing alternately in mesh with the pinion on the power-receiving shaft 70 and either of the pinions on the power-transmitting shaft. Fig. 8 is a diagram illustrating the revolving case with its pinion-carrying arms straightened out, so as to travel in a straight line. Fig. 9 is a detail view, in vertical longitudinal section, through the power receiving and transmitting shafts, showing the sliding bar carrying idle pinions and the means for operating said bar. Fig. 10 is a detail plan view of Fig. 9; and Fig. 11 is a detail 80 view, partly in vertical transverse section and partly in elevation, through line $y-y$ of Fig. 9. Fig. 12 is a view similar to Fig. 7, but having slight additions to strengthen the parts, taken upon line xx , Fig. 13. Fig. 13 is a plan view of 85 the same, taken through line $w-w$ of Fig. 12.

Referring to the parts by reference-letters, (first from Figs. 1 to 6, inclusive,) A indicates the framework of the machine, in which the power-receiving shaft B and the power-transmitting shaft C, carrying the cone-gears, are journaled. b represents the driving-pulley secured upon shaft B for receiving power from any suitable counter-shaft, and b' the loose shifting pulley journaled upon said 90 shaft B. Secured upon shaft B is a pinion B', which in length is longer than the cone-gears upon the shaft C. D represents a case or housing journaled to revolve in the frame of the machine and concentric with shaft B. 100 It surrounds the pinion B' and has projecting from it radial arms d, the ends of which

are of varying lengths. The ends of these arms are perforated to receive stud-bolts or bearings d' , upon which bearings are journaled the idle pinions d^2 of varying diameters, which 5 when the housing or case D is revolved brings one of the idle pinions d^2 in mesh with the pinion B' and one or the other of the cone-gears secured upon shaft C, case D being cut out or notched, so that the idle pinions d^2 may 10 pass through it and mesh with the pinion B' on shaft B. There is also formed integral with the case or housing D a gear-wheel D', which meshes with pinion d^3 , which is secured upon the bearing in the frame of the machine 15 and has an angularly-projecting end, upon which is secured a lever-arm d^4 , by which the casing is revolved through the gear-wheel D'.

There is a seat or notched bearing d^5 with inclined sides, over which the lever-arm d^4 20 rides and snaps into the notch to hold the casing or housing in the desired position after the lever-arm has been turned one full revolution. The pinion d^3 has one-sixth of the 25 number of teeth that are in pinion D', so that one turn of the lever d^4 revolves pinion B' and the housing one-sixth of a revolution to bring one or the other of the idle pinions d^2 in mesh with one or other of the gears upon the cone-shaft C.

30 In the metal-shaper shown in Figs. 1 and 5 the power is transmitted from shaft C through a pinion C' to the gear-wheel C², which is provided with a cam and strap to convert the rotary motion of the gear C² to a straight or 35 reciprocating movement through the link C³.

In the form shown in Fig. 7 the housing D is mounted to revolve eccentrically around the axis of shaft B and its pinion B'. The gear-wheel D' is, like the form shown in Figs. 40 1, 2, and 6; inclusive, rotated by the pinion d^3 , which is mounted in bearing on frame of the machine in all respects like the pinion shown in Figs. 1 and 4, and a handle or lever d^4 operates in the same manner; but in 45 this case it will be seen that only one of the pinions d^2 is brought in mesh with the pinion B' and one of the gear-wheels on shaft C. The mode of operating the housing D through the pinion B' is the same as is shown for operating the straight rack-bar D². (Shown in Figs. 8 to 11, inclusive.)

The rack-bar D² is mounted to slide in guideways d^6 , secured to the frame of the machine, and the pinions d^2 are mounted on 55 the ends of stud-bolts d' the same as in the preceding figures, wherein the casing is made to revolve around the shaft B instead of sliding at a right angle to it, as in Figs. 8 to 11, inclusive.

60 The variations from Fig. 7 shown in Figs. 12 and 13 will be understood from the following description: The power-receiving shaft B instead of extending across the frame of the machine and having its bearing in each side thereof only extends part way, one 65 of its bearings being in the frame A and the other bearing being in the boss or box a on

the inner end of the yoke A', which yoke is secured to the side of the machine. The yoke or bracket A' has also a box or bearing 70 in which is journaled the reduced end d of a short shaft D³, upon which is secured the gear-wheel D' and disk or plate D², in which the stud-arms d' , which carry the idle-pinions d^2 , are secured. The said shaft D³ has 75 its bearing in the frame of the machine. In other respects the parts are the same as in Fig. 7, excepting that the shell of the housing is cut away and the idle pinions d^2 are journaled at their inner ends upon stud-bolts 80 d' of varying lengths, secured in the disk or plate D². The gear-wheel D' is operated by pinion d^3 through lever d^4 , the same as shown in Figs. 1 to 5, inclusive.

Operation: Referring first to Figs. 1 to 6, 85 inclusive, it will be noticed that the operating member carrying the idle pinions at the end of the radial arms houses or incloses a long pinion B' on the power-receiving shaft B and is notched opposite the idle pinions d^2 90 to allow them to pass through the housing and mesh with the pinion B'. In this case the idle pinions are all in mesh with the pinion B', and in order to vary the speed of the machine this housing, which is mounted in 95 bearings in the frame of the machine and concentric with the shaft B, is revolved by a lever d^4 through the pinion d^3 , meshing with the gear-wheel D', which is secured on or formed integral with the housing D. If 100 the slowest speed is desired, the smallest of the idle pinions d^2 is in mesh with the largest gear-wheel c^6 , secured upon the transmitting-shaft C, and if the highest speed is desired the housing is revolved by the lever to bring 105 the larger idle pinion in mesh with the smaller gear-wheel c' , secured upon the shaft C, and the same with each of the gear-wheels, depending upon the speed desired, the proper idle pinion can be brought in mesh with the pinion B' 110 and anyone of the gears c' to c^6 , inclusive, on the power-transmitting shaft, and this operation is performed by turning the lever one full revolution, which revolves the housing one-sixth of a revolution. The lever when brought 115 to the position shown in Fig. 1 snaps into the notch in the catch d^5 and locks the housing in any desired position. The same housing, as above described, with its radial arms extending from it, is shown in Fig. 7, with the 120 housing mounted in the bearing eccentric to the shaft B, when one of the idle pinions d^2 , carried by the arms of the housing, is in mesh with the pinion B' and one of the gears on shaft C. The operation is precisely the same 125 in each case and is also practically the same in the views shown in Figs. 2 and 8 to 11, inclusive, excepting that the moving member in Figs. 8 to 11, inclusive, slides in a straight instead of a circular path.

In Figs. 12 and 13 there is no difference whatever in the mode of operating the circular moving member from that shown in Figs. 1 to 7, excepting that the power-receiving shaft 130

B is supported at the inner end by the bracket or yoke A', and the revolving idle-pinion-carrying member does not house the shaft B; but its inner projecting stud-arms and the 5 idle pinions d^2 travel around the yoke A'; but the operator actuates the moving member in precisely the same manner in all the views or modifications shown.

I have shown my invention in what I have 10 found from experience to be its simplest form; but it is obvious to those skilled in the art that many mere mechanical changes may be made without departing from the spirit or scope of my invention.

15 What I claim is—

1. In a speed-changing mechanism for machine-tools, the combination substantially as hereinbefore set forth, of the frame, the power-receiving shaft, the power-transmitting shaft, 20 both of the shafts being journaled in bearings in said frame, the pinion secured on the power-receiving shaft, gears of varying diameters forming a cone-gear secured on the power-transmitting shaft, a moving member 25 carrying idle pinions of varying diameters, the idle pinions, means to actuate the moving member to bring either of its idle pinions into mesh with the pinion on the power-receiving shaft and its companion gear on the power-transmitting shaft.

2. In a speed-changing mechanism of the character described, the combination of the power-receiving shaft, the power-transmitting shaft, a pinion secured upon the receiving-shaft, gears of varying diameters secured 35 on the power-transmitting shaft, the moving member carrying the idle pinions of varying diameters, the idle pinions, a cogged gear, also secured upon the moving member, a pinion secured on the stud-shaft, the stud-shaft, which shaft has its bearings in the frame of the machine, said pinion meshing with the cogged gear secured to the moving member, a lever to turn said pinion for the purpose of 40 actuating the moving member and a catch for the purpose of holding the lever and locking the moving member in any desired position, substantially as shown and described.

3. The combination substantially as hereinbefore set forth of a power-receiving shaft, the pinion secured thereon, the power-transmitting shaft, the cone-gears secured thereon, the moving member having radial arms of varying lengths extending from its axis or 55 path of travel, stud-shafts secured in the ends of said arms, said stud-shafts being parallel to the axis of the power-receiving and power-transmitting shafts, idle pinions of varying diameters journaled on the ends of said stud-shafts, and means to actuate the moving member for the purpose of bringing one or other of the idle pinions in mesh with the pinion on the power-receiving shaft and either of the gears on the power-transmitting shaft, and

means for locking said moving member in the 65 desired position.

4. In a speed - changing mechanism the combination of the power - receiving shaft having one of its bearings in one side of the machine and its opposite bearing in a bracket 70 or yoke secured to the same side of the machine, the bracket or yoke, a pinion on the power-receiving shaft, the transmitting-shaft, gears of varying diameters secured on the power-transmitting shaft, the moving member 75 carrying arms projecting inwardly around the power-receiving shaft, idle pinions journaled on the ends of said arms, a short shaft journaled at the front side in the frame of the machine, and having a reduced end journaled 80 in the bracket or yoke secured to the opposite side of the machine, said moving member being secured upon the inner and larger end of said shaft, a gear-wheel also secured upon said short shaft between the moving 85 member and the side of the machine and means to revolve the moving member for the purpose of bringing one of the idle gears into mesh with the pinion on the power-receiving shaft and its opposite gear - wheel secured 90 upon the power-transmitting shaft, substantially as shown and described.

5. In a speed - changing mechanism the combination of the power - receiving shaft having one of its bearings in one side of the 95 machine and its opposite bearing in a bracket or yoke secured to the same side of the machine, the bracket or yoke, a pinion on the power-receiving shaft, the transmitting-shaft, gears of varying diameters secured on the 100 power-transmitting shaft, the moving member carrying arms projecting inwardly around the power-receiving shaft, idle pinions journaled on the ends of said arms, a short shaft journaled at the front side in the frame of 105 the machine, and having a reduced end journaled in the bracket or yoke secured to the opposite side of the machine, said moving member being secured upon the inner and larger end of said shaft, a gear-wheel also secured upon said short shaft between the moving member and the side of the machine, a 110 stud-shaft journaled in the frame of the machine, a pinion, d^3 , secured on the inner end of said shaft to mesh with the gear-wheel, D', 115 a lever, d^4 , secured upon the projecting end of said stud-shaft and a catch to hold the lever and prevent the revolution of the moving member and its connections when either one of the idle pinions are brought in mesh with 120 pinion on the driving-shaft and either of the gear-wheels on the transmitting-shaft, substantially as shown and described.

JAMES MILLS.
